His Attorney.

UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

SYSTEM OF MOTOR CONTROL.

Application filed January 22, 1926, Serial No. 83,140. Renewed March 18, 1929.

My invention relates to improvements in systems of motor control and in particular to systems for controlling the acceleration of electric motors.

5 Time element control of electric motors has certain advantageous features, among which may be mentioned that of requiring the various steps of the control to proceed with always at least a certain time between 10 the various control steps. However, the ordinary forms of time element control leave something to be desired in that the time element device or devices employed are either complicated and expensive or are 15 unreliable. Furthermore, to meet satisfactorily the conditions imposed by practice in many motor applications, the time intervals between the various steps should take into account the current taken by the motor 20 so that the various steps will not be taken until the motor current has reduced to at least a predetermined value.

Objects of my invention are the provision of a time element control which takes into 25 account the practical conditions set forth and others as will be pointed out hereinafter, and the provision of a time element device which is simple, inexpensive and reliable so that the system employing such a 30 device or a plurality of such devices is simple and reliable.

For an understanding of the invention, reference is had to the accompanying drawing which shows in very simple diagram a 35 system of motor control embodying the invention.

Referring to the drawing, the electric motor 10 of the three phase alternating current slip ring type is arranged to be connected to the three phase alternating current supply circuit 11 by means of the line contactor 12. The acceleration of the motor is controlled by the resistors 13, 14 and 15, which are included in the rotor or secondary circuit of the motor. The resistor sections 13 are arranged to be short-circuited by means of the contactor 16, the resistor sections 14 by means of the contactor 17, and the resistor sections 15 are arranged 45 to be short-circuited by means of the contactor 18. The relay 19 is provided for controlling the energization of the resistor contactor 16, the relay 20 is provided for controlling the resistor contactor 17 and the

relay 21 is provided for controlling the resistor contactor 18.

The relays are substantially identical in construction and a detailed description of the construction and operation of merely the relay 19 will be given. The relay operates on the induction disc principle and is provided with an electromagnet 22 which has a series winding included in the motor circuit. This electromagnet sets up a flux through the disc 23 of non-magnetic material which produces a torque in the disc tending to rotate the same in the clockwise direction, so as to assist the bias of the spindle 24 on which the disc is mounted. The spindle 24 is supported in any suitable manner, preferably as is common in integrating wattmeters. The clockwise bias of the spindle is provided by means of the spring 25 and this insures that with the 50 windings of the relay deenergized, the switch contact member 26 will be maintained in the open position against the stop 27. The shunt electromagnet 28 is provided for setting up a substantially constant flux through the disc 23 for producing a substantially constant torque in the disc tending to rotate the same in the counter clockwise direction against the action of the series 55 electromagnet and the biasing effect of the spring 25. Each of the electromagnets 22 and 28 is provided with a pole shader, as indicated, in order to thereby effectively produce the dephased flux suitable for effectively setting up the torque in the disc. The disc 23 carries a magnetic member 29 which 60 is arranged to be rotated between the poles of the electromagnet 28, so as to thereby accelerate the closing movement of the contact 26 and to hold this contact in the closed position with a substantial effort applied 65 thereto.

One of the features of the arrangement described is that the controlling relay is very simple in construction, has relatively few parts which are liable to get out of order and furthermore operates on a general principle which is familiar to electricians charged with the maintenance of control systems such as the control system of the present invention. It will also be observed that the relay will 70 always give a certain minimum time interval of operation determined by the time required for the disc to rotate from the posi- 75

tion indicated in the drawing to the position in which the magnetic member 29 is directly between the poles of the electromagnet 28 when the switch contact 26 is in the 5 closed position. This minimum time interval will be increased, depending upon the current taken by the motor, and this effect is produced by means of the series electromagnet 22 which exerts a holding effect on 10 the relay proportional to the current taken by the motor controlled. A further advantageous feature of the arrangement is that the relays 19, 20 and 21 are mechanically independent of the resistor contactors 16, 17 15 and 18 and the line contactor 12 so that these relays may be placed at any suitable position and enclosed in a casing so as to exclude dust, moisture, and other influences which might have a detrimental effect on the 20 operation of the relays. A further feature of the invention is that by reason of the employment of the time element current limit controlling relays, the system of control is rendered very simple and effective. While 25 a particular embodiment of the invention is shown in the control of an alternating current motor, the invention is not necessarily limited thereto, but is applicable to other types of motors as well.

30 With the various parts of the system in their respective position as indicated in the drawing the operation of my invention is as follows:

In order to connect the motor to the supply circuit and effect the automatic acceleration thereof, the master switch 30 will be closed, thereby energizing the line contactor 12 to close and at the same time energizing the winding of the shunt electromagnet 28 35 of the relay 19. If the current taken by the motor 10 is in excess of the predetermined value, the series electromagnet 22 of the relay 19 will hold the disc 23 against the torque set up by the shunt electromagnet 28, 40 but if the motor current drops to the predetermined value, the torque set up by the electromagnet 28 will predominate over the biasing effect of the spring 25 and the holding effect of the series electromagnet 22 so 45 that the disc will slowly rotate in the counterclockwise direction, carrying the switch contact 26 toward the closed position. When 50 this movement is nearly completed and the switch contact is nearly in the closed position, the magnetic member 29 will be nearly within the direct influence of the flux set up by the shunt electromagnet through the disc. By reason of the fact that a relatively 55 low reluctance path for the flux of the electromagnet 28 is thus formed, the torque of the electromagnet 28 will very greatly predominate over the biasing effect of the spring 25 and the holding effect of the series electromagnet 22 and the closing movement of the switch contact 26 will be great-

ly accelerated. This is desirable because the electrical circuit controlled by the contact 26 is quickly closed and arcing at the switch contacts is thereby avoided. Furthermore, a relatively great pressure is applied to the 70 switch contacts to maintain these contacts in their closed position.

The closing of the contacts controlled by the relay switch member 26 will effect the energization of the winding of the resistor 75 contactor 16 and this contactor will close, short-circuiting the resistor sections 13. The contactor 16 will be maintained closed through an energizing circuit, independently of the relay 19 through a circuit including the auxiliary switch 31 associated with this contactor. The closing of the resistor contactor 16 will ordinarily cause the motor current to increase appreciably 80 and the relay 20 will now govern the closing 85 of the resistor contactor 17 in the same manner as the relay 19 controlled the closing of the resistor contactor 16. The closing of the contacts of the relay 19 not only energized the contactor 16, but also energized the 90 shunt electromagnet of the relay 20, thereby rendering this relay effective to introduce the time element current limit effect, in controlling the resistor contactor 17. When at 95 least the minimum time has elapsed and the current taken by the motor has reduced to the predetermined value, the resistor contactor 17 will be energized to close and short-circuit the resistor sections 14. The closing 100 of the contacts of the relay 20 will also energize the shunt electromagnet of the relay 21 so as to bring this relay into action to control the resistor contactor 18 in a similar manner to that previously explained in connection with the relay 19.

105 It will be observed that with the arrangement heretofore described, the successive closing of the resistor contactors is brought about by the successive energization of the shunt windings of the various relays and that the series electromagnets of the relay 110 are effective to positively hold the relay contacts in their open positions until the relay is set in operation to produce its time limit current limit effect, by the closing of the preceding relay of the succession or the closing 115 of some preceding switch of the succession.

What I claim as new and desire to secure by Letters Patent of the United States is:—

1. A system of control for an electric current motor comprising acceleration controlling means for the motor, and means for controlling said acceleration controlling means comprising a device having a rotatable element biased to one position, a winding connected to be energized in accordance with the motor current for setting up a flux through said element which exerts a torque on said element proportional to the value of the motor current to hold the element in said 120 125 130

- biased position, electroresponsive means for setting up a substantially constant flux through said element which exerts a counter torque tending to move the element to a 5 second position against the bias thereof and against the holding effect of said winding, the said counter torque predominating to move the element when the current taken by the motor is less than a predetermined 10 value, whereby a time interval in the control of the motor is had which is always a minimum value and is greater depending on the current taken by the motor and means comprising an armature member located at 15 the periphery of said rotatable member for increasing the counter-torque between said elements and said shunt winding as the said element approaches said second position.
2. In a system of control for an alternating current motor, electroresponsive acceleration controlling means, and means for controlling the energization of said electroresponsive means comprising an inductive device having a rotatable element biased to a 25 predetermined position, a normally open switch contact closed by said element for energizing said electroresponsive means, a series winding connected to be energized in accordance with the motor current for exerting 30 a torque on said element proportional to the value of the motor current to hold the element in said biased position, a shunt winding which normally sets up a substantially constant counter torque on said element tending to rotate the same and effect 35 the closure of said contact against the bias of said element and the holding effect of said series winding, and means for increasing the counter torque set up in said element by said 40 shunt winding as the said contact approaches the closed position and when said contact is in the closed position.
3. In a system of control for alternating current motors, a plurality of contactors arranged to be closed in a definite succession for controlling the motor, a separate relay for controlling each of a plurality of said contactors to control the speed of the motor, each of said relays having a rotatable element 45 biased to a predetermined position, switch contact mechanism controlled by said element for controlling the contactor associated with said relay, a series winding connected to be energized in accordance with the 50 motor current for exerting a torque on said element proportional to the value of the motor current tending to hold the element in said biased position, a shunt winding which sets up a substantially constant torque 55 on said element tending to rotate the same to effect operation of said contact mechanism against the bias of said element and the holding effect of said series winding, the torque of said shunt winding predominating 60 over the bias of said element and the torque 65 of said series winding when the motor current has dropped to a predetermined value, and connections through which the shunt winding of each relay is energized in response to the operation of a preceding contactor of the succession to effect the successive closing of the contactors with a time interval between the closing of successive contactors which is always a minimum value and is greater depending on the current 70 taken by the motor.
4. An electroresponsive acceleration controlling device for alternating current electric motors comprising a disc, a winding arranged to be energized in accordance with 80 the motor current for setting up a series characteristic torque tending to rotate the disc in one direction, a second winding for setting up a shunt characteristic torque tending to rotate the disc in the opposite direction, the torque of said series characteristic winding predominating over the torque of said shunt characteristic winding when the motor current is above a predetermined 85 value and the torque of said shunt characteristic winding predominating over the torque of said series characteristic winding when the motor current is less than said predetermined value, a magnetic armature so mounted on said disk as to increase the 90 torque between said shunt winding and said disk when the latter is rotating in said opposite direction, and switch contacts controlled by said disc for controlling the motor.
5. An electroresponsive acceleration controlling device for alternating current motors comprising a disc biased to one position, a series electromagnet arranged to be energized in accordance with the motor current for setting up a series characteristic 100 torque tending to rotate the disc in one direction, a shunt electromagnet angularly disposed with reference to said series electromagnet for setting up a counter torque in said disc, the torque of said series electromagnet and the bias of said disc predominating over the torque of said shunt electromagnet when the motor current is above a predetermined value and the torque of said shunt electromagnet predominating over the 105 torque of said series electromagnet and the bias of said disc when the motor current is less than said predetermined value, normally open switch contacts operated by said disc to and from the closed position, and a magnetic member on said disc for increasing the torque of said shunt electromagnet as the said contacts approach the closed position and when said contacts are in the closed 110 position.
- In witness whereof, I have hereunto set my hand this 20th day of January, 1926.
- BENJAMIN W. JONES.
